UNITED STATES PATENT OFFICE.

FRANK B. EELLS, OF CHICAGO, ILLINOIS, ASSIGNOR TO INTERNATIONAL TIME RECORDING COMPANY OF NEW YORK, A CORPORATION OF NEW YORK.

THREE-RIBBON RECORDER.

1,388,177.

Specification of Letters Patent. Patented Aug. 23, 1921.

Application filed July 26, 1919. Serial No. 313,579.

To all whom it may concern:

Be it known that I, FRANK B. EELLS, a citizen of the United States, residing at Chicago, in the county of Cook and State of Illinois, have invented certain new and useful Improvements in Three-Ribbon Recorders, of which the following is a full, clear, and exact description.

In a great number of industrial establishments at the present time it is customary for each employee to keep a card upon which he records his in and out time for given periods, at the end of which he turns in his card to a clerical force which computes therefrom his working time for which he is entitled to pay. In large establishments, where cards are turned in by the thousands, a vast amount of clerical work is required to read each card and compute the total time therefrom, and numerous plans have been proposed and some practically adopted to reduce this work and render the computation of actual time easier, deducting late and adding overtime.

For this purpose I propose that each employee's card shall be printed in one color to show proper or normal time, in another color to show late or abnormal time, and in a third color to show overtime, so that no examination of any card printed in the color which indicates normal or regular in and out times need be made in computing total time, but only those that bear imprints in one or the other colors. In handling a mass of cards, therefore, only those which show unusual colors need be laid aside for closer examination while all others may be passed as showing full normal time.

To carry out this plan I have devised a recording machine capable of printing in a plurality of colors, three being sufficient to meet all ordinary contingencies, and associated with such machine I use a program attachment which at specified and predetermined moments sets for operation the means for printing in the color which is designed for records made at such times.

The machine which I have designed for this purpose is one having a three colored ribbon, and by means of a program attachment I provide for printing from the middle or normal color say blue, all times recorded up to two minutes after seven a. m., from the lower color or red, all times from 7.02 to 12, from blue again from 12 to 1.02, from red

again from 1.02 to 5.02 or 6.02 p. m., as the case may be, and from the upper color or green from 5.02 to approximately 7 a. m., when the registrations again are made in blue.

A card printed wholly in blue will therefore show that its owner's in and out times throughout the week were approximately on the regular working hours. A red impression shows at a glance that he was late, or a green impression that he worked overtime.

This machine is shown in the accompanying drawings in which—

Figure 1 is a view in elevation of the complete recorder.

Fig. 2 is a view in elevation of the interior mechanism.

Fig. 3 is a plan and part sectional view of the means for supporting the ribbon spools.

Fig. 4 is a detail of the ribbon shifting mechanism.

Fig. 5 is a detail of a cam used in the machine.

Fig. 6 is a cross-section of the same.

Fig. 7 is a detail of a ratchet for operating the cam, and

Fig. 8 is an elevation of a modified form of mechanism for shifting the ribbon.

Much of the machine illustrated in these drawings is well known in the art and in extensive use, so that a detailed description of it is not necessary in this case. The machine comprises a card chute 1, in which a workman inserts his card for registering and the usual or any means are employed for varying the position of the card for receiving in and out imprints. A handle or lever 2 is provided for operating a printing hammer 3, and the proper mechanism for indicating time is used but not fully illustrated.

The main spindle of the time mechanism is indicated by 4, and a horizontal shaft 5, gearing therewith, drives the program dial 6, all of these parts being of the usual construction.

The multicolored inking ribbon 7 is carried by two spools 8, and the usual or any proper means are employed for reversing the movement of the spools when the ribbon has all been fed in one or the other direction. The spools surround and turn with but are free to move longitudinally in spindles 9, and, as shown in Fig. 3, are carried by a

frame 10 pivoted on the shaft 11, which may be shifted and to thereby bring either the upper or the lower part of the ribbon between the type wheels and the printing hammer. The means for effecting this shifting are as follows:

To the program disk or dial 6 are attached a certain number of stops 12, the position of which may be changed at will. A lever 13, pivoted to the end of a fixed arm 14 has a rounded projection 15 which normally lies in the path of the stops 12 and whenever this projection is encountered by a stop the lever 13 is raised. This movement of lever 13 is imparted by a link 16 to a pawl 17, operating on a ratchet 18 with which is associated a stop pawl 19. The ratchet has an arbitrary number of teeth, twelve being a convenient number and that shown.

On the shaft of and rotated step by step by the pawl 18 is a cam 20 which may have any conformation which the special necessities of the case requires as will be understood from what follows: On the periphery of this cam disk 20 bears a roller 22 carried by one arm of a bell crank lever 21, pivoted at 23 to the frame, and to the other arm of said lever is pivoted a bar 24, suitably guided and capable of a sidewise as well as a vertical movement.

To the printing lever or any rigid part oscillated thereby is pivoted a horizontally reciprocating link 25, having a slot 26 in its end through which passes a pin 27 on the bar 24 so that whenever the handle is operated a movement to the left is imparted to the said bar 24.

The upper end of bar 24 is bifurcated and has two straight edge jaws 28 inclining toward a central groove 29, and this bifurcated end is adapted to engage a pin 30 in one of the side bars 32 of the frame 10 pivoted on the shaft 11, and having a bifurcated end that engages with pins 31 set in the spool frame.

Let it be assumed that at any time after 6 a. m. the position of the ratchet 18 and cam disk 20 is such that the roller 22 carried by lever 21 is running on the normal periphery of the cam disk. Under such conditions the vertical position of the arm 24 is normal, and if it be operated by the printing lever or handle it will swing to the left until the pin 30 enters its central groove 29, but will neither raise nor depress the ribbon spool. All impressions thus taken, therefore, will be in the normal color, for example, blue.

A stop 12 however is so set on the program dial that it raises the lever 13 at 7.02, and this moves the ratchet 18 and turns cam 20 so that the roller 22 will now rest upon one of the high parts of the cam, and in consequence the arm 24 will be raised. If an impression be taken while this condition

exists, the lower jaw of the bifurcated end of lever 24 will encounter the pin 30 and the latter sliding up the incline will raise the spool frame to bring the red or lower color band of the inking ribbon opposite the type and the printing hammer. This means that any time registered after 7.02 will be printed in red until the cam 20 is again moved, and for this purpose another stop may be set at the desired point, say 12 o'clock 75 to raise the lever 13 and move the cam 20 so as to bring the roller back to the normal periphery of the cam. If this is done all registrations between 12 and the moment for which another stop is set, usually 1.02 p. m., 80 will be again printed in blue, but if at 1.02 the cam be again moved it will cause the printing to be done in red until the normal end of the working day, when the cam is again moved to print blue.

Another stop may be set to move the ratchet and cam another step shortly after the closing time whereby the roller may run for any predetermined time on a depression in the cam, which will operate to depress 90 the arm 24 and thereby cause the upper jaw of said arm to lower the spool when an impression is taken so that the printing is done by the upper or green color band on the ribbon. This will indicate overtime.

There are few mechanical details of the device that require further elaboration in view of the knowledge now possessed by all those skilled in the art, but certain of the more important ones may be pointed out.

To relieve the thrust on the arm 24 during the printing operation, I employ a fixed plate 35 with three notches or indentations into one or another of which a pin 36' on the arm 24 enters when said arm is thrown forward by the printing handle, according to whether said arm is in its normal, its elevated or its depressed position.

Another device which insures the proper normal position of the spool frame is composed of the lever 36, pivoted to the shaft 11, connected by a spiral spring 37, and normally held by said spring against fixed stops 38 whenever the spool frame is released from engagement with the arm 24. These levers 115 center the side bar 32 and bring the central color band on the ribbon into position to print.

When a ratchet 18 with a certain small number of teeth is used, it should be caused 120 to make a complete revolution each day, for which purpose as many stops 12 may be set to lift the bar 13 during the night or between working hours, as may be necessary.

The specific means described for raising 125 and lowering the arm 24 are not of the essence of my invention and any other proper instrumentalities may be employed. For example, as shown in Fig. 8, the program disk may send at certain times current im-

pulses to an electro-magnet 39, the armature of which carries a pawl 40 that operates a ratchet wheel 41. This ratchet operates a cam 42 upon which bears a roller in the arm 5 of a bell crank lever 43, and when the roller is on a high point on the arm the arm 24 is raised, when it is on a low point the arm is in its normal position.

On the other hand, a second magnet 44 10 operates a similar cam upon the periphery of which another arm 45 of lever 43 is adapted to bear when the first described roller is not on a high point of cam 42, and when arm 45 rides a higher point on cam 15 44 the arm 24 is depressed.

Such modification in the proportions and form of the elements herein shown and described as may be desired to meet particular requirements will be readily understood 20 from the nature, purpose and functions of the parts above set forth.

It is not broadly new in this art to set an inking ribbon by a program or timing device so that it will print in different colors at different times, but no such mechanism has heretofore been proposed which was capable of normally printing in one color and of changing at will to other colors as provided for in my machine.

30 What I claim is:

1. In a workman's time recorder, the combination with a multicolored inking ribbon and a movable carrier therefor, of a lever having a movable pivotal support and which is adapted by its engagement with the ribbon carrier to raise or lower the same according 35 to the elevation of its pivotal support, a time controlled cam mechanism including a high cam surface, a low cam surface, and an intermediate cam surface, for varying the elevation of said pivotal support and a printing means which, when operated, brings the said lever into engagement with the carrier.

2. In a workman's time recorder, the combination with a multicolored inking ribbon and a movable carrier therefor, of a lever for raising and lowering said carrier from its normal position, a lever engaging the carrier lever for adjusting its pivotal support whereby it will raise or lower the carrier lever when engaging therewith a high cam surface, a low cam surface, and an intermediate cam surface, in operative relation to said adjustable lever, and a printing handle or lever connected with the said adjustable lever and adapted to throw it into engagement with the carrier lever in the operation of printing.

3. In a workman's time recorder, the combination with a multicolored inking ribbon and a movable carrier therefor, automatic means for maintaining the carrier in normal position, a lever for raising and lowering said carrier when engaging therewith, a time controlled mechanism including a high

cam surface, a low cam surface and an intermediate cam surface for adjusting said lever so that it may raise or lower the carrier, and a printing lever or handle connected with the adjustable lever and adapted to bring the same into engagement with the carrier in the operation of printing.

4. In a workman's time recording machine, the combination with a multi-colored inking ribbon and a carrier therefor, of a printing mechanism coöperating with said ribbon, and means for selecting one of at least three-colored portions of said ribbon when the printing mechanism is operated.

5. In a workman's time recording machine, the combination with a multi-colored inking ribbon and a carrier therefor, of a printing mechanism coöperating with said ribbon, and time controlled means for selecting one of at least three colored portions of said ribbon when the printing mechanism is operated.

6. In a workman's time recorder, in combination with a multicolored inking ribbon, of a printing mechanism coöperating with said ribbon for printing time imprints upon a record surface, and time controlled means having provisions for effecting the printing of normal in-and-out time impressions in one color upon said record surface, said means having provision for printing abnormal in-and-out time impressions in a different color upon said surface and having provision for printing overtime impressions in still a different color whereby a rapid segregation of 95 normal, late and overtime records may be secured.

7. In a workman's time recorder, in combination, a multicolored inking ribbon, a printing mechanism coöperating therewith for printing time impressions therefrom upon a record surface, time controlled means for controlling the relation of said printing means and ribbon, said means having provision for so controlling the relation of the printing mechanism and ribbon as to present one color at certain time periods, another color at other time periods and a still different color at other periods of time.

8. In a workman's time recording machine, in combination, a multicolored inking ribbon, a printing mechanism coöperating with said ribbon for printing time impressions therefrom upon a record surface, time controlled means for controlling the relation of said printing means and ribbon, said means being biased for normal operation to print through one section of the ribbon for normal in and out time operations, said means having provision for relatively shifting the printing mechanism and ribbon to produce impressions of a different color for abnormal in and out time impressions and having provision for differently relatively shifting the printing mechanism and ribbon to pro-

duce impressions of a third and different color for in and out overtime time impressions.

9. In a workman's time recorder, in combination with a multicolored inking ribbon and a movable carrier therefor, a printing handle or lever, means for normally retaining the ribbon carrier to print one color upon the operation of the printing handle, 10 of time controlled mechanism having provision for controlling the shifting of the carrier in either of two directions from its normal position upon the operation of the printing handle whereby either of the other 15 two colors will be printed, depending upon the time of printing the impression.

10. In a workman's time recorder, in combination, a multicolored inking ribbon adapted to impart at least three different colors to 20 the coöperating record surface, a carrier therefor, means for taking impressions from said ribbon, and time controlled means biased for normal operation to cause the impressions to

be taken in a given color, and means associated therewith for controlling shifting to 25 one of the other of the plurality of colors when impressions are taken at certain time periods.

11. In a workman's time recorder, in combination with a multicolored inking ribbon of a printing mechanism coöperating with 30 said ribbon for printing time imprints upon a record surface, and time controlled means having provisions for effecting the printing of impressions made at certain times in a predetermined color upon said surface, said means having provisions for effecting the printing of impressions made at certain other times in a different color upon said 35 surface, said means also having provisions for effecting the printing of impressions made at certain other times in a still different color. 40

In testimony whereof I affix my signature.

FRANK B. EELLS.
